UNITED STATES PATENT OFFICE

171,542

COMBINATION BROILER AND BRAZIER

Dean S. Harrel, Los Angeles, Calif., assignor to
Harrel & Co., Los Angeles, Calif., a limited
partnership doing business as World's Best
Broiler Brazier Mfg. Co., Ltd.

Application September 14, 1953, Serial No. 26,800

Term of patent 14 years

(Cl. D81—10)

To all whom it may concern:

Be it known that I, Dean S. Harrel, a citizen
of the United States, residing in Los Angeles, in
the county of Los Angeles and State of California,
have invented a new, original, and ornamental
Design for a Combination Broiler and Brazier,
of which the following is a specification, refer-
ence being had to the accompanying drawings,
forming part thereof.

Fig. 1 is a top plan view of a combination
broiler and brazier, showing my new design.

Fig. 2 is a side elevational view thereof.

Fig. 3 is a vertical sectional view, as taken on
the line 3—3 of Fig. 2.

I claim:

The ornamental design for a combination
broiler and brazier, substantially as shown.

DEAN S. HARREL.
